Jean O. Reinecke, Oak Park, Ill., assignor to McGraw Electric Company, Elgin, Ill., a corporation of Delaware

Application May 23, 1947, Serial No. 139,223

Term of patent 14 years

(Cl. D49—6)

To all whom it may concern:

Be it known that I, Jean O. Reinecke, a citizen of the United States, residing in the city of Oak Park, county of Cook, and State of Illinois, have invented a new, original, and ornamental Design for an Electric Iron, of which the following is a specification, reference being had to the accompanying drawings, forming a part thereof, in which

Fig. 1 is a perspective view of an electric iron showing my new design;

Fig. 2 is a top plan view thereof; and

Fig. 3 is a side elevation.

Figs. 2 and 3 are shown on a reduced scale.

I claim:

The ornamental design for an electric iron, substantially as shown.

JEAN O. REINECKE.
